UNITED STATES PATENT OFFICE.

CHRISTIAN L. BERGER, OF BOSTON, MASSACHUSETTS.

DESIGN FOR A TRIVET.

No. 38,078.

Specification for Design.

Patented June 12, 1906.

Application filed April 1, 1905. Serial No. 253,370. Term of patent 14 years.

To all whom it may concern:

Be it known that I, CHRISTIAN L. BERGER, a citizen of the United States, residing at Boston, in the county of Suffolk and State of Massachusetts, have invented a new, original, and ornamental Design for Trivets, of which the following is a specification, reference being had to the accompanying drawings, forming part thereof.

In the drawings, Figure 1 is a perspective

view of my design. Fig. 2 is a view thereof in side elevation. Fig. 3 is a top plan view thereof.

I claim—

The ornamental design for a trivet, as shown.

CHRISTIAN L. BERGER.
